UNITED STATES PATENT OFFICE.

CHARLES E. ELKINS AND THOMAS B. SMITH, OF WACO, TEXAS.

VENDING MACHINE.

Application filed October 23, 1924. Serial No. 745,438.

To all whom it may concern:

Be it known that we, CHARLES E. ELKINS and THOMAS B. SMITH, citizens of the United States, residing at Waco, in the 5 county of McLennan and State of Texas, have invented certain new and useful Improvements in Vending Machines, of which the following is a specification, reference being had to the accompanying drawings.

10 This invention relates to vending machines, and particularly to machines for vending pencils or like articles.

The general object of the invention is to provide a very simple, easily operated machine of this character which includes a valve-like receiver having a shape approximately the same as a pencil and adapted to receive the lowest pencil of those contained within the magazine and, when oscillated, 20 to deliver said pencil and prevent the other pencils from being discharged.

A further object is to provide improved means whereby the device may not be actuated to discharge a pencil unless a coin has 25 been deposited.

Other objects will appear in the course of the following description.

Our invention is illustrated in the accompanying drawings, wherein:

30 Figure 1 is a front elevation of a pencil vending machine constructed in accordance with our invention, the lower part of the machine being in section;

35 Figure 2 is a fragmentary vertical section showing the manner in which the pencils are discharged;

Figure 3 is a fragmentary elevation of the coin operating means, the magazine being in section;

40 Figure 4 is an elevation of the coin operating means, the coin chute being in section;

Figure 5 is a like view to Figure 3 but showing the receiver rotated to its discharged position;

45 Figure 6 is a like view to Figure 4 but showing the receiver rotated to its discharged position;

Figure 7 is a vertical section on the line 50 7—7 of Figure 3;

Figure 8 is a like view to Figure 7 but showing the receiver rotated to discharge the pencil;

55 Figure 9 is a fragmentary elevation of one end of the case 10 showing the operating means on the exterior of the case.

Referring to these drawings, 10 designates opposite walls of a case or cabinet forming part of the vending machine. Within this case or cabinet is disposed the pencil magazine 11, and disposed below the lower end of the case or cabinet is a pencil chute 12. The forward and rear walls of these parts 11 and 12 are connected by means of the intermediate, outwardly bowed 60 portions 13, as illustrated in Figure 7. These outwardly bowed portions 13 define a chamber within which is disposed an oscillatable receiver 14. This receiver is cylindrical in cross section, except in its middle or that portion which extends through the magazine 11 or more correctly through the part 13, and is hollow so that the middle portion of the receiver, as illustrated in Figure 7, forms a semi-circular receptacle, the 70 total depth of the receptacle being equal to the diameter of a pencil A. One extremity of this receiver is oscillatably mounted in a bearing 15 carried upon one side wall 10 and the opposite end of the receiver is oscillatably supported, as will be now described.

Mounted in a bearing bracket 16 upon the opposite side wall of the receiver is a longitudinally extending shaft or pin 17 which enters the adjacent end of the receiver 14 and thus supports the latter and constitutes a bearing therefor. This shaft or pin 17 is held to the bracket 16 by means of a transverse pin 18 which prevents the shaft 17 80 from rotating and prevents it from any sagging movement. Any means might be used

to firmly support the end of the shaft 17 so that it will be directly in line with the receiver 14 and act as a bearing therefor. A 85 pin 19 passes through the tubular receiver and abuts against the end of the shaft 17. Beyond the pin 18 the receiver 14 has an angular extension 20. This extension 20 is provided, as illustrated in Figure 4, with a laterally projecting, curved lug 21. Confronting this arm or extension 20 is a second arm 22, the lower end of which has a sleeve 23 which rotates loosely upon the bearing shaft 17, and the inner face of this arm is 90 provided with a slight cup-shaped coin support 24 which has the shape of a segment of a circle the size of a coin.

Disposed immediately above the normal position of this cup-shaped coin support 24 110 is a coin chute 25 which extends downward from the exterior of the vending machine

in any suitable manner, the lower end of this chute being angularly cut away, as at 26, so that the rear wall of the coin chute is lower than the front wall and approximates 5 the upper edge of the cup when the arm 22 is in its rearward position. The arm 22 is provided with a laterally projecting rod 27 to which an operating lever, arm or other 10 operating device exterior to the vending machine may be connected so that upon an operation of this operating device in one direction the arm 22 will be drawn over in a counter-clockwise direction in Figure 4. A coiled spring 28 is connected at one end 15 to the bracket 16 and at its other end is connected to the sleeve 23 or the arm 22 and resists this movement of the arm, and when the force which is applied to moving the arm is released this arm 22 returns to its 20 normal position. The same is true of the arm 20. One end of the receiver 14 has surrounding it a coiled torsion spring 29 which at one end is attached to the bearing 15 and at the other end to the receiver and acts 25 also to return the receiver to its normal position. The spring 28 also acts to force the sleeve 23 forward to force the arm 22 toward the arm 20 so that but little more space is left between the inner faces of the two arms 30 than is necessary to receive a coin in the normal position of these parts. When, however, the arm 22 is turned over to the position shown in Figure 6, a cam-shaped face 35 30 which is at the lower end of the arm 22 engages a pin 31 and this forces the arm 22 away from the arm 20 against the action of the spring 28 when the arms 20 and 22 are in the dotted line position shown in Figure 5, thus permitting the dropping out of 40 the coin in the normal position of the parts. The arms 22 and 20 are disposed as illustrated in Figure 4, the arm 20 being somewhat in advance of the arm 22 and the arm 22 being in such position that the cup 24 is disposed immediately beneath the rear portion 45 of the coin chute 25. At this time the receiver 14 is disposed as illustrated in Figure 7, with its open face up, and the lowest pencil A of the series of pencils within the 50 magazine 11 is resting in this receiver.

If now a coin be deposited in the chute 25, it drops down the chute and lands upon the cup 24. If now the arm 22 be moved forward by means of any suitable operating mechanism connected with the rod 27, the coin will move along until it strikes the lug 21, and after that the arm 20 will move with the arm 22. This continues until the arms are in a depending position, as illustrated in 55 Figure 5. The coin up to this time has been firmly clamped between the arms; but when this position is reached the pin 31 engaging against the cam edge 30 forces the sleeve 23 outwardly, thus separating the two arms so 60 that the coin may drop out. At the time 65

that the arms have reached their depending position, the receiver 14 has become completely overturned and drops the pencil out, as shown in Figure 8, the rounded bottom of the receiver being now upward preventing any other pencil from dropping downward through the pencil chute. As soon as the coin has dropped out, the spring 29 will act to return the member 14 to its initial position, and as soon as the force has been released from the arm 22, this arm will return to its normal position. As soon as the receiver returns to its normal position, a new pencil will drop into the receiver and all is ready for another actuation. The coin, of course, drops into a suitable coin box located below the arms 20 and 22. 70 75 80

While we do not wish to be limited to any particular form of operating means for the arm 22, we have illustrated a rod 27 connected to the operating member 22 crank-shaped at its end to extend through a slot 32 formed in the case 10. We have illustrated this rod 27 as being formed at its extremity with a guide 27^a whereby the rod may be oscillated to oscillate the arm 22, but we do not wish to be limited to this as any other means might be used for this purpose. 85 90

We have not endeavored in these drawings to illustrate the general design or form of a pencil vending machine but only such parts as are necessary for an understanding of the operation and actuation of the device, and while the parts as illustrated have been found particularly simple but yet efficient, we do not wish to be limited to the details of construction as these obviously may be modified in many ways without departing 100 from the spirit of the invention as defined 105 in the appended claims.

We claim:—

1. A coin controlled mechanism including an oscillatable member, an arm mounted upon said member, an oscillatable arm approximately confronting the first named arm, means for manually oscillating the second named arm, a coin chute, means carried by said first-named arm for receiving the coin from the chute, said coin acting as means for interlocking the two arms with each other for unitary oscillatory movement, and means for causing the separation of the two arms when they have reached a predetermined point to thereby permit the dropping of the coin. 110 115 120

2. A coin controlled mechanism including an oscillatable member, an upwardly extending arm on the oscillatable member, a second upwardly extending arm approximately confronting the first named arm and oscillatably mounted, means connected to said second named arm whereby it may be manually oscillated, a coin chute discharging immediately above the normal position of the second named arm, a segment-shaped coin 125 130

- cup carried by the second named arm, the first named arm having a lug disposed in the path of movement of the coin carried by said cup whereby said arms may have 5 unitary movement, and means for causing the separation of the arms when the arms have been oscillated to a depending position to thereby permit the discharge of the coin.
- 10 3. In a coin actuated mechanism, an oscillatable member having an upwardly extending arm on one end, a second upwardly extending arm approximately confronting the first named arm and oscillatably mounted, means connected to said second named arm whereby it may be manually oscillated, a coin chute discharging immediately above the normal position of the second named arm, a segment-shaped coin cup 15 carried by the second named arm, the first named arm having a lug disposed in the path of movement of the coin carried by said cup whereby said arms may have unitary movement, means for causing the separation of the arms when the arms have been oscillated to a depending position to thereby permit the discharge of the coin, and means for returning both of said arms to their normal position after the coin has 20 been discharged.
- 25 4. A coin controlled mechanism including a tubular oscillatable member, a bearing supporting one end of the tubular member, a fixed shaft extending into the other 30 end of the tubular member and supporting it for oscillation, the last named end of the member having a radially extending arm, a sleeve mounted upon the shaft and having a radially extending arm approximately confronting the other arm, means for 35 manually oscillating the last named arm and sleeve, a spring yieldingly urging the last named sleeve toward the first named sleeve and yieldingly resisting rotation of the last 40 named sleeve, means yieldingly resisting the rotation of the first named sleeve, and means for causing a movement of the second named 45
- sleeve away from the first named sleeve when the arms are in a depending position comprising a pin mounted upon the 50 shaft, the sleeve having a cam face engaging with said pin to cause separation of the arms when the sleeves have rotated sufficiently to carry the arms to a depending position. 55
5. A coin actuated device comprising two confronting oscillatable members mounted for rotation upon a common axis and having radially extending approximately confronting arms, one of the arms being provided with a coin cup and the other with a lug disposed in advance of the coin received in said cup, means for oscillating the coin cup carrying arm to carry the coin into engagement with the lug to thereby cause unitary oscillation of the two arms, and means for causing a lateral separation of the two arms when the arms have reached a depending position to thereby cause the discharge of the coin. 60
6. A coin actuated device for vending machines comprising two confronting oscillatable members mounted for rotation upon a common axis and having radially extending approximately confronting arms, one of the arms being provided with a coin cup and the other with a lug disposed in advance of the coin received in said cup, means for oscillating the coin cup carrying arm to carry the coin into engagement with the lug to thereby cause unitary oscillation of the two arms, and means for causing a lateral separation of the two arms when the arms have reached a depending position to thereby cause the discharge of the coin including a member exerting a camming action on one of said oscillatable elements to shift it laterally away from the other element when the arms have reached a depending position. 65
- 70
- 75
- 80
- 85
- 90

In testimony whereof we hereunto affix our signatures.

CHARLES E. ELKINS.
